UNITED STATES PATENT OFFICE

2,490,684

FIREMAN'S HOOK

Eugene A. Gosselin, St. Petersburg, Fla.

Application April 26, 1946, Serial No. 665,288

1. Claim. (Cl. 81—3)

1
The present invention relates to new and useful improvements in tools for use by firemen for the purpose of removing wall and ceiling materials in event of fire, such as metal ceilings, plaster and similar wall and ceiling coverings and the primary object of the invention is to provide a device for this purpose which may be more readily employed and with better results than is obtained through the use of hooks now in use.

A further object of invention is to provide a tool of this character embodying spring means for exerting its force in a manner to penetrate the wall or ceiling whereby to aid in cutting through metal or plaster material.

A further object of invention is to provide a novel construction whereby the spring actuating means for the cutting edge of the hook is alternately contracted and expanded whereby to exert rapid hammer blows on the wall or ceiling by the hook to penetrate or cut into the wall or ceiling.

A still further object is to provide a tool of this character of simple and practical construction, which is efficient and reliable in use, strong and durable and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary longitudinal sectional view showing the cutting head of the hook in projected position.

Figure 2 is a similar view showing the cutting head in retracted position.

Figure 3 is a transverse sectional view taken on a line 3—3 of Figure 2.

Figure 4 is a detail, in elevation, of the trip for releasing the plunger, and

Figure 5 is a similar view taken at right angles to Figure 4.

Referring now to the drawing in detail wherein for the purpose of illustration I have disclosed a preferred embodiment of invention, the numeral 5 designates a portion of a wooden or lightweight metal handle having a barrel 6 secured to its outer end in longitudinal alignment with the handle in any suitable manner, such as by telescoping one end of the barrel over the handle and securing the barrel thereto by means of a rivet or the like 7.

A cap 8 is threaded on the outer end of the barrel and is formed with a central opening 9

through which a plunger 10 is slidably mounted, the plunger having a longitudinally extending groove 11 forming a key-way in which a key 12 carried by the cap 8 is received to prevent rotation of the plunger in the barrel.

To the outer end of the plunger 10 is secured a transversely extending cutting head 13 of substantially spear shaped-construction.

An annular guide 14 is secured in the barrel 6 intermediate its inner and outer ends by means of screws or the like 15 and in which the plunger is slidably mounted and a collar 16 is formed on or fixed to the plunger intermediate its ends for engaging the cap 8 to limit outward movement 15 of the plunger and cutting head 13. A coil spring 17 is positioned in the barrel 6 between the guide 14 and collar 16 to exert its influence on the plunger to project the plunger and cutting head 13 outwardly of the barrel. A hammer 20 designated generally at 18 is slidably mounted in the barrel 6 inwardly of the guide 14, the hammer including a tubular portion 19 having an annular head 20 formed at its outer end and in which the inner end of the plunger 10 is slidably received. The tubular portion 19 of the hammer is formed with a transverse opening 21 extending therethrough and in which a tubular trip 22 is positioned for transverse sliding movement.

Secured to one side of the tubular portion 19 30 of the hammer is a leaf spring 23 extending longitudinally of the hammer and having a free upper end curved inwardly and bearing against one side of the trip 22 to urge the same laterally in the tube 19 out of alignment therewith as shown in Figure 1 of the drawing. The lower end of the plunger 10 is formed with a reduced extension 24 forming a shoulder 25 at the lower or inner end of the plunger adapted for engagement by the upper edge of the trip 22 to provide

35 for an inward or downward movement of the hammer 18 by a retracting movement of the plunger 10 and head 13.

The tubular portion 19 of the hammer is of a diameter less than that of the barrel 6 and is 45 adapted to enter a sleeve 26 retained in the inner end of the barrel. The upper end of the sleeve 26 is bevelled as shown at 27 and the lower edge of the trip 22 is also bevelled as shown at 30 and adapted for engagement with the bevelled edge 27 50 of the sleeve to slide the trip laterally to align the trip with the tubular portion 19 of the hammer and to release the hammer from the inner end of the plunger 10 upon the inward or retracting movement of the plunger 10.

55 A coil spring 31 is positioned in the sleeve 26

in engagement with the inner end of the hammer 18 to drive the hammer upwardly or outwardly in the barrel 6 upon releasing thereof by the trip 22 whereby to cause a hammer blow against the collar 14 which functions as an anvil and thus cause an impact on the cutting head 13.

Describing in detail the use and operation of the invention; in the normal position of the parts, the plunger 10 is extended out of the barrel 6 with the collar 16 thrust against the cap 8 by the spring 10 17. The trip 20 is held by the spring 23 in a position to engage the shoulder 25 on the plunger 10. Now, by exerting pressure on the handle 5 in the direction of the cutting head 13, with said head pressed against a wall, the barrel 6 is moved forwardly along the plunger 10 to compress the springs 17, 31. This causes the bevel end 27 of the sleeve 26 to engage the bevel 30 on the trip 20 and thereby cam the trip 20 out of engagement with the shoulder 25 in opposition to the spring 23. This releases the hammer 18 to slide forwardly on the plunger 10, and at the instant of release, the spring 31 projects the hammer 18 against the guide 14, or anvil, causing an impact against the tensioned spring 17 which is transmitted to the plunger 10 through said spring 17 and the collar 16 to drive the cutting head 13 into the wall, or the like. Upon release of pressure on the handle 5, the plunger 10 is returned to the normal position described. Under the impact against the 30 plunger 10, the same is driven forwardly sufficiently to permit the trip 20 to be again engaged with the shoulder 25 by the spring 23.

In view of the foregoing description taken in conjunction with the accompanying drawings it 35 is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described 45 and the scope of the appended claim.

What I claim is:

A fireman's hook comprising a plunger having a front end cutter thereon, a handle having a front end barrel thereon out of which said plunger projects, said plunger being mounted in said barrel for sliding of the barrel forwardly thereon, an annular anvil fixed in said barrel and slidable on said plunger with said barrel, a coil spring in said barrel forwardly of said anvil projecting said plunger out of the barrel and compressible by sliding of said barrel and anvil forwardly on the plunger, whereby to press said cutter against an object under tension, a second coil spring in said barrel in the rear of said anvil, an annular hammer in said barrel between said anvil and second coil spring slidable forwardly in said barrel and on said plunger and including a spring pressed trip normally engaging the rear end of the plunger, whereby sliding of said barrel and anvil forwardly causes the second coil spring to be compressed and said anvil to move forwardly of said hammer, said trip being releasable to disengage the rear end of the plunger, whereby under the reaction of the compressed second coil spring said hammer is slid forwardly against the anvil to cause impact against the compressed coil spring first mentioned for driving the cutter into the object, and means in said barrel coacting with said trip to release the same when said barrel and anvil have been slid forwardly on the plunger in predetermined degree.

EUGENE A. GOSSELIN.
